UNITED STATES PATENT OFFICE.

QUINTUS I. SIMPSON, OF PALMER, ILLINOIS.

DESIGN FOR A STAY FOR WIRE FENCES.

SPECIFICATION forming part of Design No. 25,885, dated August 4, 1896.

Application filed June 22, 1896. Serial No. 596,544. Term of patent 7 years.

To all whom it may concern:

Be it known that I, QUINTUS I. SIMPSON, of Palmer, in the county of Christian and State of Illinois, have invented a certain new Design for Stays for Wire Fences, of which the following is a specification.

In the drawings forming part of this specification, Figure 1 is a face view of a stay, showing my design; and Fig. 2 is a side view 10 of the same, the terms "face" and "side" being used with relation to the position of the stay in a fence. Fig. 3 is a cross-section, on an enlarged scale, on line *x* in Fig. 2. Fig. 4 is a cross-section on line *y*, same figure. 15 The stay, which is designated in the drawings by reference-letter *a*, is a cylindrical rod

having in one side a number of transverse depressions, as shown at *b*. The depressions are concave or semicylindrical, and the intervals between them increase in distance from 20 the bottom of the rod upward.

Having thus described my invention, what I claim, and desire to secure by Letters Patent, is—

The design for a stay for wire fences, substantially as shown and described. 25

In testimony whereof I sign my name in the presence of two subscribing witnesses.

QUINTUS I. SIMPSON.

Attest:

J. F. MILLER,
U. H. DAWES.
